SAND TOY

Robert G. Fitzgerald, Syracuse, N.Y.
(178 Phillips Road, Sagamore Beach, Mass. 02652)

Filed June 17, 1969, Ser. No. 17,744

Term of patent 14 years

Int. Cl. D21—02

U.S. Cl. D34—15

FIG. 1

FIG. 2

FIG. 3

FIG. 1 is a plan view of the sand toy, embodying my new design;

FIG. 2 is a side elevational view thereof with a part broken away; and

FIG. 3 is a front end elevational view thereof.

I claim:

The ornamental design for a sand toy, substantially as shown and described.
